United States Patent Office

Des. 226,441
Patented Mar. 6, 1973

226,441

VELOCIPEDE

Viktor Schreckengost, Cleveland Heights, Ohio, assignor to The Murray Ohio Manufacturing Co., Nashville, Tenn.

Filed June 25, 1971, Ser. No. 157,067

Term of patent 14 years

Int. Cl. D12—11
U.S. Cl. D34—15 AL

Fig. 2

Fig. 3

Fig. 5

FIG. 1 is a front perspective view of a velocipede showing my new design;

FIG. 2 is a right side elevational view thereof;

FIG. 3 is a top plan view thereof;

FIG. 4 is a front elevational view thereof; and

FIG. 5 is a rear elevational view thereof.

I claim:

The ornamental design for a velocipede, substantially as shown.
